CLAIM

The ornamental design for a cleaning wipe system, as shown and described.

DESCRIPTION

FIG. 1 is a front-top-left perspective view of a cleaning wipe system;
FIG. 2 is a rear-top-right perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a reduced exploded front-top-left perspective view thereof, revealing a twist-off locking mechanism;
FIG. 10 is a magnified view taken about circle 10 in FIG. 9; and,

FIG. 11 is a reduced exploded front-bottom-left perspective view thereof, revealing the twist-off locking mechanism.
